UNITED STATES PATENT OFFICE.

CHARLES A. SHIELDS, OF MONTREAL, QUEBEC, CANADA.

BUTTON.

No. 893,945.

Specification of Letters Patent.

Patented July 21, 1908.

Application filed February 19, 1907. Serial No. 358,224.

To all whom it may concern:

Be it known that I, CHARLES A. SHIELDS, a citizen of the United States of America, residing at Montreal, in the Province of Quebec 5 and Dominion of Canada, have invented new and useful Improvements in Buttons, of which the following is a specification.

This invention relates to buttons, and one of the principal objects of the same is to provide a button with a hinged head, said head being of such contour and being pivoted to a post in such a manner that the head can be easily inserted in a button hole of a stiffly starched neck-band or cuff.

15 Another object of the invention is to provide a button with a hinged head, the head being of substantially ovoid shape and provided with a groove in its underside to form a recess for the post of the button when said 20 button head is turned into alignment with said post on either side thereof, for inserting the head into a button-hole.

These and other objects may be attained by means of the construction illustrated in 25 the accompanying drawing, in which:

Figure 1 is a side elevation of a button made in accordance with my invention, the head of the button being swung against the side of the post in position for entering the 30 head into a button-hole. Fig. 2 is a plan view of the button with the head swung to a right angle to the post in position for holding the button engaged with the button-hole. Fig. 3 is a central, vertical section of the 35 button with the head swung at right angles to the post in position for holding the button in engagement with the button-hole. Fig. 4 is an underside plan view of the head of the button, and showing a modified form of 40 hinge or pivot for the post of the button.

Referring to the drawings for a more particular description of my invention, the numeral 1 designates the shoe of the button, 2 is the post or shank, and 3, is the pivoted 45 head.

As shown in the drawing, the button is of the collar button type, but it will be understood that a cuff button, or a button for other purposes may be made in accordance with 50 my invention.

The shoe 1 and the post 2 may be made in-

tegral, or the post may be properly secured to the shoe. The post is flat and its upper end is curled to form a pivot bearing, as at 4. The button head 3 is provided with a groove 55 or recess 5 extending from end to end of the major axis of said head, and on the underside thereof, said groove or recess being of a depth sufficient to inclose within it the post 2 when the button head is tipped to the position shown in Fig. 1. A pintle or pivot pin 6 extends through the minor axis of the button head, said pintle spanning the recess 5, and engaging the pintle bearing 4 of the post 2. As shown, the head 3 is substantially ovoid 65 in shape, and when said head is swung down against the post 2 a wedge-like entering point 7 is provided which will separate the walls of a button-hole even if very stiffly starched, and gradually spread the button-hole suf- 70 ficiently to permit it to pass over the button head and onto the flat shank 2, after which the button head may be swung to the position shown in Figs. 2 and 3, from which position it cannot be accidentally disengaged from 75 the button-hole. The button head 3 may be swung upon either side of the post 2 without interfering with the operation of entering the head 3 in the button-hole.

As shown in Fig. 4 the pintle 6^a is formed 80 integral with the button head 3^a, and the upper end of the post 2 may be curled around such a pintle after it has been inserted in the groove or recess 5^a in an obvious manner.

From the foregoing it will be obvious that 85 a button head made in accordance with my invention, may be secured to a flat post attached to a shoe of any suitable construction.

A button made in accordance with my invention, being of simple construction, composed of comparatively few parts, can be manufactured at slight cost, is strong and durable, has no projecting parts to catch and injure the edges of the button-hole, can be quickly applied and removed from the button-hole, and is very efficient and reliable 95 in use.

Having thus described the invention, what I claim is:

A button comprising a shoe, a post secured 100 to said shoe and extending at right angles thereto, and a head pivoted to said post, said

head being substantially ovoid in contour and provided with a groove or recess in its underside extending across its major axis, said post being pivotally connected to the 5 button head by a pintle which spans said recess or groove, and that portion of said post within the length of said head being adapted to lie wholly within said groove or recess

when the button head is tipped upon its pivot to either side of said post.

In testimony whereof, I affix my signature in presence of two witnesses.

CHARLES A. SHIELDS.
